INVENTOR

Norman de Beaumont

BY

W. Fairbank
ATTORNEY

UNITED STATES PATENT OFFICE.

NORMAN DE BEAUMONT, OF NEW YORK, N. Y.

BUTTON.

1,359,038.

Specification of Letters Patent. Patented Nov. 16, 1920.

Application filed July 10, 1920. Serial No. 395,299.

To all whom it may concern:

Be it known that I, NORMAN DE BEAUMONT, a citizen of the United States, and a resident of New York city, in the county 5 of New York and State of New York, have invented certain new and useful Improvements in Buttons, of which the following is a specification.

This invention relates particularly to the 10 means employed for attaching a button to a garment or other supporting article, the main object being to provide flexible connections of substantial character so that the button may readily tilt in respect to the 15 supporting article to facilitate buttoning and unbuttoning, and the button and its attaching means may be easily and inexpensively manufactured and attached by single machine or hand operation.

Among the various other objects of my invention are to reduce liability of tearing 20 the goods to which the button may be secured and to reduce the extent to which the button projects from the surface when unbuttoned.

In the accompanying drawings I have 25 illustrated certain embodiments of my invention but it will, of course, be obvious that other forms might be readily designed within 30 the scope of my invention as defined in the appended claims.

In these drawings:

Figure 1 is a central longitudinal section 35 through one form which my invention may assume and a portion of an article to which the button may be attached, the parts being shown in an enlarged scale and the supporting article of possibly exaggerated thickness.

Figs. 2 and 3 show similar sections 40 through other forms.

In the form shown in Fig. 1 there is provided a button 10 which may be of metal, bone, hard rubber, or other material or composition and of any desired shape or size 45 depending upon the character of the garment or other supporting article to which it is to be attached. The body portion of the button has a shank 11 preferably of metal 50 and terminating in an enlarged head 12 presenting a curved bearing surface and preferably in the form of a ball or sphere. The shank 11 may be secured rigidly to the body portion of the button or if the button be of 55 suitable character, as for instance metal, the

stud may be formed integral with the body of the button. The shank is shown as extending through a central aperture and as having its upper or outer end 13 deformed, flattened or riveted over to prevent withdrawal. 60

The means for connecting the shank to a supporting article of sheet form, such for instance as the article 14, is shown as including two telescoping members 15 and 16. 65 The member 15 projects through the supporting article 14 and has a base flange 17 of a size depending upon the character of the article 14 and limiting the outward movement of the member 15. The member 70 16 has a similar base flange 18 and is slightly larger than the member 15 so as to telescope thereon. The members 15 and 16 fit together friction tight so that when forced together by a suitable machine or hand tool, the garment or other supporting article 14 will be firmly gripped between the two flanges 17 and 18. The tubular portion of the member 15 has an internal diameter which is preferably slightly larger than the outside diameter of the head 12, while the upper or outer end of the tubular member 16 is approximately hemispherical with a central aperture slightly larger than the shank 11 but smaller than the head 12. The length of 85 the shank 11 may be such that the distance between the head 12 and the lower side of the button 10 is only slightly greater than the thickness of the material constituting the socket forming the upper end of the member 16. This is not essential as the shank 11 may be of materially greater length so that it may telescope into member 15 to a limited extent when unbuttoned. 90

In assembling, the shank 11 is preferably 95 extended through the member 16 to bring the ball and socket in proper co-operative relationship and the shank is then extended through the central aperture of the button and the head 13 is formed to prevent withdrawal of the shank. The parts 10, 11 and 16 are permanently connected. When the button is to be secured to a garment or other supporting article, the member 15 is projected through an aperture in the article 100 105 and the members 15 and 16 forced together. Although in some cases it may be desirable to slightly deform these members after the telescoping operation is completed so as to prevent their separation, I preferably rely 110

upon a tight friction fit so that in case there is excessive strain on the button the members 15 and 16 will separate before the member 15 tears out of the supporting article.

- 5 The upper end of the member 15 may be made of thinner or more easily deformed material than the socket portion of the member 16, and the member 15 may be made of such length that upon telescoping the end 10 of the member 15 will be contracted above the head 12 and thus form a lining for the socket and transmit the strain of any pull on the button, directly to the member 15 and its base flange 17. It will be noted that the 15 operation of attaching the button to the supporting article is a very simple one, easily accomplished by machine or hand pull operation or in emergency might be forced by the flanges 17 and 18 toward each other 20 merely by hand. As the pull on the button is not ordinarily in a direction at right angles to the plane of the supporting surface, this pull will ordinarily tend to tilt the member 16 rather than pull it directly off from 25 the member 15 and thus the friction fit of the two members will be sufficient to resist any ordinary strain. The button may freely tilt in any direction to facilitate buttoning or unbuttoning, but the connecting means is 30 such that there is little or no liability of wearing out or getting out of order. Obviously the tubular member 15 may be made somewhat shorter than as shown in Fig. 1 so that there is no contracting of the upper 35 end when the parts are connected.
- In Fig. 2 I have shown another form in which the same button and shank with its ball end 12 are employed. The tubular member 16^a instead of telescoping with the 40 tubular member 15^a has its base flange 18^a spun or bent around a flange at the end of the member 15^a so as to permanently connect these parts. A washer 19 is employed instead of the flange 17 and in assembling 45 the parts the member 15 is projected through the material and one end is spun

or forced over to form a flange 20 permanently connecting all the parts to the sheet 14.

In Fig. 3 I have shown a further form in which the shank 11^b is somewhat longer and the member 16^b is formed flat instead of hemispherical as in Fig. 2. In this form the shank lies within the member 15^a and the latter is constructed and connected the same as in the form shown in Fig. 2.

I do not wish to be limited to any particular character of material for the sheet 14 as it may be of comparatively heavy fabric, or several layers of fabric, or may be 6 leather, or any other similar sheet material.

Having thus described my invention what I claim as new and desire to secure by Letters Patent is:

1. In combination a pair of members 6^a adapted to telescope and having base flanges for gripping a supporting article therebetween, one of said members terminating in a socket at its outer end, and a button having a shank terminating in a ball within 70 said socket.

2. In combination, a pair of tubular members adapted to telescope and having base flanges for gripping a supporting article therebetween, the outer of said tubular members terminating in a socket at one end, and a button having a shank terminating in a ball within 75 said socket.

3. In combination, a pair of tubular members adapted to telescope and having base 80 flanges for gripping a supporting article therebetween, the outer of said tubular members terminating in a socket at one end, and a button having a shank terminating in a ball within 85 said socket, said tubular members fitting friction tight and adapted to separate upon a strain less than that required to tear said supporting article.

Signed at New York city in the county of New York and State of New York this 90 ninth day of July A. D. 1920.

NORMAN DE BEAUMONT.
